(57) **CLAIM**

The ornamental design for a torque wrench, as shown and described.

DESCRIPTION

FIG. 1 is a front perspective view of a first embodiment of a torque wrench showing my new design;
FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front perspective view of a second embodiment of a torque wrench;
FIG. 10 is a rear perspective view of FIG. 9;
FIG. 11 is a front elevation view of FIG. 9;
FIG. 12 is a rear elevation view of FIG. 9;
FIG. 13 is a left side elevation view of FIG. 9;
FIG. 14 is a right side elevation view of FIG. 9;
FIG. 15 is a top plan view of FIG. 9; and,
FIG. 16 is a bottom plan view of FIG. 9.
The evenly broken lines in the drawings illustrate portions of the torque wrench that form no part of the claimed design.
